(57) **CLAIM**

The ornamental design for a tile frame, as shown and described.

DESCRIPTION

FIG. 1 is a perspective rear view of a tile frame;

FIG. 2 is a rear view thereof;

FIG. 3 is a front perspective view thereof;

FIG. 4 is a left side view thereof (the right side being a mirror image of the left side); and,

FIG. 5 is a top side view thereof (the bottom side being a mirror image of the top side).

The broken lines shown in the drawings are included for the purpose of illustrating portions of the tile frame and form no part of the claimed design.

1 Claim, 4 Drawing Sheets
